UNITED STATES PATENT OFFICE.

MAHLON C. FRISBIE, OF ST. LOUIS, MICHIGAN.

SILO.

1,106,868.

Specification of Letters Patent. Patented Aug. 11, 1914.

Application filed June 4, 1913. Serial No. 771,718.

To all whom it may concern:

Be it known that I, MAHLON C. FRISBIE, a citizen of the United States, residing at St. Louis, in the county of Gratiot and State of Michigan, have invented a new and useful Silo, of which the following is a specification.

The device forming the subject matter of this application is a silo and the object of the invention is to provide a novel form of wall construction.

It is within the scope of the invention to improve generally and to increase the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings:—Figure 1 shows in front elevation, a silo constructed in accordance with the present invention, parts being broken away; Fig. 2 is a fragmentary transverse section on the line 2—2 of Fig. 1; and Fig. 3 is a fragmental longitudinal section on the line 3—3 of Fig. 1.

The silo herein disclosed comprises in inner wall 1, preferably made up of upright boards 2, tongued and grooved together as indicated at 3. Disposed upon the outside of the inner wall 1 is a filler 4 which may be fashioned from felt, paper or the like, or from some other material which is a good insulator of heat. Superposed upon the filler 4 is an outer wall 5, the same preferably comprising upright boards 6, tongued and grooved together as indicated at 7, the boards 6 of the outer wall 5 being disposed in lap-joint relation to the boards 3 of the inner wall 1.

The silo is preferably of octagonal form to facilitate the building of the roof (not shown). Further, owing to the octagonal form of the silo, the same may readily be built of true and upright form, so as to rest properly upon the supporting foundation 8 which preferably is fashioned from concrete.

Embedded in the foundation 8 are anchors 9 each anchor being connected as at 18 with

a pedestal 17. In transverse section, the pedestal 17 is wedge-shaped.

Applied to the side faces of the pedestals 17 are uprights 19 which may be angle members, one flange of each angle member lying along the outer face of the outer wall 5. Bolts 20 pass through the lower ends of the uprights 19 and through openings formed in the pedestal 17. Posts 21 are supported upon the upper ends of the pedestals 17, between the uprights 19. The posts 21 are of wedge shape in cross section, and correspond to the pedestals 17 in cross section. The posts 21 are held in place by bolts 22 which, as clearly shown in Fig. 2, pass through the outwardly projecting flanges of the uprights 19.

Retaining bars 23 extend between the posts 19, the retaining bars 23 being recessed in their rear edges, to receive the rear flanges of the uprights 19, as will be best understood from Fig. 2. Bolts 24, appearing in Fig. 1, connect the end portions of the retaining bars 23 with the rear flanges of the support 19. Angle members 25 surround the lower, outer corners of the retaining bars 23 and are substantially co-equal in length with the retaining bars. The angle members 25 are held in place by securing elements 26, one of which is shown in Fig. 3. Between the upper edge of the outer flange of the angle member 25 and the upper edge of the retaining bar 23 there is a space adapted to receive nails 27, holding in place a facing 28 which may be fashioned from wood or metal. Between the facing 28 and the outer wall 5 there exists a dead air space 29 which, together with the wall construction hereinbefore described, renders a freezing of the contents of the silo unlikely, even in climates subject to an extremely low temperature.

If desired, the rectangles defined by the corner posts 21 and the retaining bars 23 may be strengthened by counters 30, the constituent members of each counter being connected by turn buckles 31. The counters 31 may be located at any desired height, and any number of counters may be employed, between the top and the bottom of the silo.

Having thus described the invention, what is claimed is:—

In a structure of the class described, a pair of upright angle members including forwardly presented flanges defining an acute angle 1 with each other and laterally presented flanges defining an obtuse angle with each

other; a wedge shaped post secured between the forwardly presented flanges; and a wall comprising coöperating corner forming elements, one of which elements upon its outer 5 face fits against the laterally presented flange of one angle member and is beveled along its upright edge to fit against the laterally presented flange of the other angle member to one side of the wedge, the other 10 corner forming element fitting upon its outer face against the last specified laterally pre-

sented flange and being beveled upon its upright edge to engage with the rear face of the first specified corner forming element.

In testimony that I claim the foregoing as 15 my own, I have hereto affixed my signature in the presence of two witnesses.

MAHLON C. FRISBIE.
